RIGHT ANGLE DRIVE AND PEDESTAL

John G. Fenic, Donald L. Kime, and William C. Raridan,
Dayton, and Read C. Viemeister, Yellow Springs, Ohio,
assignors to Chemineer, Inc., Dayton, Ohio

Filed Dec. 18, 1972, Ser. No. 315,923

Term of patent 14 years

Int. Cl. D15—05

U.S. Cl. D55—1 D

FIG. 1 is a perspective view of a right angle drive and pedestal, with a motor shown in broken lines for illustrative purposes only;

FIG. 2 is a front view thereof;

FIG. 3 is a top view thereof;

FIG. 4 is a side view thereof; and

FIG. 5 is a rear view thereof.

We claim:

The ornamental design for a right angle drive and pedestal, substantially as shown and described.
